UNITED STATES PATENT OFFICE.

ALFRED E. SMITH, OF BRONXVILLE, NEW YORK.

WASHER FOR AXLES.

Specification of Letters Patent No. 13,327, dated July 24, 1855.

To all whom it may concern:

Be it known that I, ALFRED E. SMITH, of Bronxville, Westchester county, and State of New York, have invented a new and useful Improvement in Packing-Washers for Carriage and other Axles, of which the following is a full, clear, and exact description, reference being had to the accompanying drawings, making part of this specification, 10 in which—

Figure 1, is a face view of the said improved washer; and Fig. 2, a cross section thereof.

The same letters indicate like parts in all 15 the figures.

My invention consists in making packing washers for axles of leather or other equivalent flexible and yielding material, with blocks of metal or other equivalent hard substance inserted through the substance of the 20 washer to prevent the rapid wearing away of the leather.

In the accompanying drawings *a* represents an annulus of leather such as is commonly used on the axles of carriages at the 25 end or ends of the box. Such packing washers, as heretofore made of leather alone, wear away very soon on the two faces and become so thin that they have to be removed. To 30 prevent this too rapid wearing away of the leather I insert through the thickness of the

leather copper rivets *b*, *b*, *b* three in number, more or less, and hammer them down so that they shall present a thickness slightly less than the thickness of the leather, so that 35 when the leather is slightly compressed between the shoulders of the axle or journal and box the said metallic shoulders shall run in contact with the ends of the rivets, and thus prevent the too rapid wearing away of 40 the leather surfaces, such as would take place if not protected by the metal rivets.

It will be obvious from the foregoing that instead of the copper rivets above specified other metals or hard wood may be substituted. And although I prefer to secure the 45 blocks in the leather as described they may be inserted without riveting. And it will also be obvious that other substances such as gutta percha may be substituted for the 50 leather.

What I claim as my invention and desire to secure by Letters Patent is—

Inserting blocks of metal or other equivalent hard substance in packing washers made 55 of leather or other equivalent flexible and yielding substances, substantially as and for the purpose specified.

ALFRED E. SMITH.
